UNITED STATES PATENT OFFICE

132,351

DESIGN FOR A SHOE

Richard P. Boothby, Auburn, Maine, assignor to
Air-Tred Shoes, Inc., Auburn, Maine, a corpora-
tion of Maine

Application August 13, 1941, Serial No. 102,819

Term of patent 3½ years

To all whom it may concern:

Be it known that I, Richard P. Boothby, a citizen of the United States and a resident of Auburn, Maine, in the county of Androscoggin and State of Maine, have invented a new, original, and ornamental Design for a Shoe, of which the following is a specification, reference being had to the accompanying drawing, forming a part thereof, in which,

Fig. 1 is a plan view of a shoe showing my new design, and

Fig. 2 is a side elevational view thereof.

In both views the heel end of the shoe is shown conventionally in dot and dash lines.

The dominant feature of my design consists in an upper of oxford tie pattern having a moccasin type vamp, a pair of saddle straps rising from the sole line at the shank of the shoe and having scalloped edges, a plurality of elongated oval lacing loops secured to said saddle straps, and a tongue extending upward from the throat of the vamp and having a scalloped upper edge.

I claim:

The ornamental design for a shoe substantial-
ly as shown and described.

RICHARD P. BOOTHBY.
